(57) **CLAIM**

The ornamental design for a cylindrical camera pan and tilt base, as shown and described.

DESCRIPTION

FIG. 1 is a top, front and right side perspective view of a cylindrical camera pan and tilt base, shown in condition of use with an unclaimed cylindrical camera body;

FIG. 2 is a top, front and right side perspective view of a cylindrical camera pan and tilt base;

FIG. 3 is a bottom, back and left side perspective view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof;

FIG. 9 is a bottom plan view thereof;

FIG. 10 is a reduced exploded top, front and right side perspective view of a cylindrical camera pan and tilt base, shown in condition of use with an unclaimed smart device and adapter; and,

FIG. 11 is a reduced top, front and right side perspective view of a cylindrical camera pan and tilt base, shown in condition of use with an unclaimed smart device and adapter.

The broken lines depict portions of a cylindrical camera pan and tilt base in which the design is embodied and form no part of the claimed design. The broken lines in FIGS. 1, 10 and 11 depicting a cylindrical camera body, smart device and adapter are included for the purpose of illustrating environmental subject matter and form no part of the claimed design.
